UNITED STATES PATENT OFFICE.

BENJAMIN J. KNAPP, OF ST. PAUL, MINNESOTA.

LUBRICATING JOURNAL-BEARING.

SPECIFICATION forming part of Letters Patent No. 639,250, dated December 19, 1899.

Application filed March 21, 1899. Serial No. 709,875. (No model.)

To all whom it may concern:

Be it known that I, BENJAMIN J. KNAPP, of St. Paul, Ramsey county, Minnesota, have invented certain Improvements in Lubricating 5 Journal-Bearings, of which the following is a specification.

My invention relates to improvements in journal-bearings; and it consists in the construction hereinafter particularly described 10 and claimed.

In the accompanying drawings, forming part of this specification, Figure 1 is a cross-section of a journal-box, showing my improved bearing; and Fig. 2 is a detail of my 15 bearing.

In the drawings, A represents the journal-box, 2 the journal, and 3 the supporting framework. The journal-box is of ordinary construction, having the space below the journal 20 for holding packing. (Not shown.) 4 represents the bearing-brass, which rests upon the upper portion of the journal.

My invention consists of transverse grooves 5, formed in the inner face of the bearing-brass 4. These grooves extend inward only 25 a short distance from the side edges of the

brass, leaving a central bearing-surface 6, which rests upon the top of the journal, as shown in Fig. 1. In use the oil passes from the packing (not shown) in the lower part of 30 the journal-box through the grooves 5 and is carried by the journal in its revolution along said grooves and out of their inner ends to and upon the ungrooved central portion of the bearing, thus keeping the journal thoroughly 35 lubricated.

I claim—

A bearing of the class described, formed with transverse grooves in its bearing-face, said grooves extending only a short distance 40 inward from each side of the bearing, leaving an ungrooved bearing-face between the two rows of grooves whereby the lubricant is fed to the ungrooved central portion of the bearing. 45

In testimony whereof I affix my signature in the presence of two witnesses.

BENJAMIN J. KNAPP.
